HAIR CURLER

Blanche Elsie Beadle, Springfield, Mass.

Original application July 7, 1934, Serial No. 734,071. Divided and this application March 4, 1937, Serial No. 128,885

8 Claims. (Cl. 132—41)

This invention relates to hair curling devices and has particular reference to devices for rolling up the ends of hair and holding the hair in rolled form until it sets.

Hair curling devices of this type, known generally as "end-curlers", have been made in various forms, all characteristic in that they include a cylindrical body around which the hair is rolled inwardly from its ends, and a locking member attached to the body at one end and detachably connected thereto at its free end for securing the hair in rolled position while the curl sets. Various arrangements have been adopted for detachably connecting the free end of the locking member to the body and these include spring catches which soon lose their resiliency, rubber bands which are rapidly deteriorated by the hair treating oils and compounds used to set the hair, and other forms of connecting means which do not remain effective.

In accordance with the present invention, a hair curling device of the end curler type is provided which is free from the aforementioned objections in that the free end of the locking member is positively secured to the body without the use of spring latches, rubber bands or the like, and in such a way that it cannot be detached except intentionally. In addition, the new hair curler is durable and does not lose its effectiveness upon exposure to hair treating compounds.

In the new hair curling device the lock between the body and the free end of the locking member is obtained by a relative longitudinal bodily movement between the body and the pivoted member. This relative movement enables locking cooperation between the corresponding free ends of the body and the locking member, preferably by the insertion of a part of the locking member in the end of the body or vice versa, so that a positive lock is made at an angle to the direction of the closing and opening movements of the pivoted locking member. Elastic bands and spring latches are accordingly dispensed with, and a positive but readily releasable lock is provided between the locking member and the body.

This application is a division of my application Serial No. 734,071, filed July 7, 1934, which discloses several forms of my new hair curling device. The device of the present application is characterized in that the locking member is connected indirectly to the hair rolling body in such a way that it can pivot with respect thereto. More particularly, the device of the present in-

vention comprises a hair rolling body having a locking member pivoted indirectly at one end to one end of the body and bodily movable longitudinally with respect thereto, so that the free end of the locking member may be releasably secured to the free end of the body. In one form of my new device, a lip is pivoted on the body for initially clamping the hair prior to the application of the locking member, and the locking member is carried by the lip. The lip is bodily movable longitudinally of the hair rolling body to carry the locking member into and out of position for locking its free end to the corresponding end of the hair rolling body.

In another form of my invention, the lip is pivoted to the hair rolling body on a hinged pin, and the latter is perforated for the sliding reception of the inner ends of the locking member. The locking member is accordingly movable bodily of the hair rolling body in a longitudinal direction to move the free end thereof into and out of locking relation with the free end of the hair rolling body. Alternatively, only one connection between the locking member and the pivot pin may be employed.

The hair rolling body of the new device may be made of metal or of a non-metallic material, such as rubber, or metal covered with rubber.

It will be seen that a hair curling device made in accordance with the present invention overcomes the objections to the usual types of end curling devices, and that a very simple and inexpensive device is provided which is positive in action.

For a more complete understanding of my invention, reference may be had to the accompanying drawing in which

Fig. 1 is a side view of one form of my new hair curling device;

Fig. 2 is a similar view of another form of the new device; and

Fig. 3 is another view of the device shown in Fig. 2.

Referring to Fig. 1 of the drawing, the numeral 10 designates a tubular body of metal, such as aluminum, although it may be made of rubber or other non-metallic material, or of metal coated with rubber or other non-metallic material, depending upon requirements. The lower end of the body is provided with an integral, outwardly turned finger piece 11.

Pivoted to the body 10 by means of a pivot pin 12, is a lip 13 having a semi-circular contour, that is, a contour conforming to the contour of the outer surface of the body 10, so as to partially

- embrace the latter. The pivot pin 12 passes through longitudinal slots 14 formed on opposite sides of lip 13 near the lower end thereof. The lower end of the lip 13 is also provided with an 5 outwardly turned finger piece 15 cooperating with the finger piece 11 of body 10 and normally urged therefrom by a leaf spring 16. The leaf spring 16 engages the inner surfaces of finger pieces 11 and 15 which are recessed to hold and enclose the 10 spring 15, and the ends of the spring are seated on inwardly extending flanges 11' and 15' formed on the body 10 and lip 13 respectively. The lip 13 is accordingly normally urged against the body 10 and serves to clamp the hair which is rolled 15 around the body 10 in the manner of a curling iron. It will be apparent that by reason of the slots 14 formed in lip 13, the latter may be moved bodily on its pivot in a longitudinal direction relative to the body 10.
- 20 A generally U-shaped locking member 17 is pivoted on the lip 13 near the lower end thereof. The pivotal connection of member 17 to the lip may be conveniently effected by inserting the 25 ends of its arms in openings formed in opposite sides of the lip above the slots 14. The cross bar 18 of the U-shaped locking member is adapted to be received in notches 19 formed in the free end of the tubular body 10.
- It will be understood that when lip 13 is in its 30 lowermost position relative to the body 10, the leaf spring 16 is evenly disposed in the finger pieces of the body 10 and lip 13. That is, substantially one-half of the spring is contained in the body 10 and the other half in the lip. However, when the lip is moved to its uppermost position with respect to the body, as shown in Fig. 1, the leaf spring is deformed from its normal position. Consequently, the upward movement of the 35 lip on its pivot pin is opposed by the spring 16, and the latter serves to urge the lip towards its lowermost position relative to the body. If desired, a spring (not shown) may be arranged within the body 10 for supplementing the action of the spring 16 in urging lip 13 downwardly when it is moved 40 to its uppermost position relative to the body 10.
- In the use of the device shown in Fig. 1, the hair is wrapped around the body 10 and clamped thereto by lip 13. The hair is then locked in place by moving the lip 13 upwardly relative to body 10 and aligning the cross piece 18 of locking member 17 with notches 19. The lip 13 is then allowed to move downwardly longitudinally of the body to engage the cross member 18 in the notches 45 19.
- 50 The curler illustrated in Figs. 2 and 3 comprises a hair rolling body 10a and a lip 13a which are connected together by a pivot pin 12a rotatable in the body 10a. The ends of the pin 12a project through openings formed in the opposite sides of the lip and the body and are provided with transverse openings. Each of the transverse openings in pin 12a receives one leg of a generally U-shaped locking member 17a, the legs being 55 slideable in the openings. The extreme end of each leg of the locking member is provided with an enlargement 20 which prevents it from being withdrawn from the corresponding opening in the pivot pin 12a. The free end of the locking member 17a is formed with a downwardly turned projection 21 for insertion into the open free end of the body 10a when the locking member is moved downwardly from the position shown in Fig. 2. Alternatively, only one of the legs of 60 locking member 17a need be employed, together 70 with the inturned projection 21 thereon. When

only one leg of the locking member is employed a cotter pin is inserted in the opposite opening in the pivot pin 12a to prevent the latter from being withdrawn. In the latter form of the locking member, the projection 21 is preferably enlarged 5 transversely so that it frictionally engages the inner walls of the body 10a, so as to hold the locking member 17a in locked position. If desired a compression spring (not shown) may be coiled around each leg of member 17a between the pivot 10 pin 12a and the enlargement 20 on the leg, so that the locking member will normally be urged downwardly with respect to the hair curling body. Preferably, a leaf spring 16a is received in suitable recesses formed in the lower ends of body 10a 15 and lip 13a. The spring 16a engages the inner surfaces of finger pieces 11a and 15a formed on the body 10 and lip 13, respectively, and urges the lip against the body so as to clamp the hair thereto.

20 It will be observed that the hair curler of the present invention is characteristic in that the locking member is moved bodily longitudinally of the hair rolling body to effect locking and unlocking of its free end with the corresponding 25 end of the body. The locking engagement between the free ends of the locking member and the body is positive and secure, so that accidental or unintended release of the locking member is impossible, it being necessary for the user 30 to effect positive relative longitudinal movement between the body and the locking member to release them from each other.

While two preferred embodiments of my invention have been illustrated and described in detail 35 herein, it is to be understood that the invention is not limited thereby, but is susceptible to various changes in form and detail within its scope.

I claim:

1. A hair curling device which comprises an 40 elongated body, and a locking member connected indirectly to the body at one end adjacent one end of the body and pivotable with respect thereto, said body and member being bodily movable longitudinally of each other to effect a connection 45 and disconnection of their free ends.

2. A hair curling device comprising an elongated body, a member pivoted to said body, and a locking member connected to said pivoted member and releasably connectible at its free end to 50 the corresponding free end of the body, said body and locking member being bodily movable longitudinally of each other to effect the connection and disconnection of their free ends.

3. A hair curling device comprising an elongated body, a lip hinged to the body adjacent one end thereof and normally urged against the side wall of the body, a locking member carried by said lip and releasably connectible at its free end to the corresponding free end of the body, 60 said lip being movable longitudinally of said body to effect the connection and disconnection of the free ends of said body and locking member.

4. A hair curling device comprising an elongated body, a lip hinged to the body adjacent 65 one end thereof and normally urged against the side wall of the body, a locking member carried by said lip and releasably connectible at its free end to the corresponding free end of the body, 70 said lip and body being movable bodily longitudinally of each other to effect the connection and disconnection of their free ends, and means for urging said body and lip longitudinally toward each other when the locking member is in posi- 75

tion for connection of its free end to the corresponding end of the body.

5. A hair curling device comprising an elongated body, a lip pivotally connected adjacent one end to one end of the body, said connection being loose to permit longitudinal bodily movement between the lip and body, and a locking member pivoted at one end on the lip and releasably connectible at its free end with the free end 10 of the body, said movement between the body and lip permitting the connection and disconnection of the free end of the body and member.

6. A hair curling device comprising an elongated body, and a locking member connected at 15 one end through a pivotal connection to the body adjacent one end thereof and releasably connectible at its free end to the corresponding free end of the body, said pivotal connection including a lateral projection mounted on the body and having an opening in which the locking member is longitudinally slidable to effect the connection and disconnection of the free ends of the body and member.

7. A hair curling device comprising an elongated body, a pin extending transversely through the body near one end thereof and rotatable relative thereto, and a locking member mounted on said pin with one end of the member extending through a transverse opening in the pin and its 5 free end releasably connectible to the corresponding free end of the body, said locking member being slidable longitudinally of said body in said opening to effect the connection and disconnection of the free ends of the body and member. 10

8. A hair curling device comprising an elongated body, a pin extending transversely through the body near one end thereof and rotatable relative thereto, said pin having a transverse opening near each end thereof, and a U shaped locking member mounted on said pin with the legs of the locking member extending through said transverse openings in the pin and with its free end releasably connectible to the corresponding free end of the body, said locking member being 15 slidable longitudinally of the body in said openings to effect the connection and disconnection of the free ends of the body and member.
